Primary Examiner — Patricia A Palasik

(57) **CLAIM**

The ornamental design for a press housing, as shown and described.

DESCRIPTION

FIG. 1 is a perspective view showing the press housing embodying the new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in the drawing views are included for the purpose of illustrating portions of the press housing only, and form no part of the claimed design.

1 Claim, 4 Drawing Sheets---
